UNITED STATES PATENT OFFICE

2,263,450

ADJUSTABLE CHAIR

Einar Anderson, New York, N. Y.

Application July 25, 1940, Serial No. 347,384

5 Claims. (Cl. 155—116)

This invention relates to new and useful improvements in an adjustable chair.

The invention proposes an adjustable chair which is characterized by a flexible frame having a pair of spaced forwardly extending feet portions for resting on the ground and continuing into upwardly extending front portions continuing into rearwardly extending side portions, and a transverse back portion for supporting a chair back depending from the rear ends of the side portions in a particular manner.

More specifically, it is proposed that the chair back be pivotally mounted on said transverse back portion.

Still further the invention proposes the provision of a chair seat pivotally connected with said chair back and extending forwards and rested on said horizontal bar and adapted to maintain various positions on the horizontal bar.

Still further the invention proposes an arrangement for varying the distance of said transverse back portion from said side portions.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an adjustable chair constructed in accordance with this invention.

Fig. 2 is a perspective view of the chair shown in Fig. 1 with the parts in a different position.

Fig. 3 is a fragmentary enlarged vertical sectional view taken on the line 3—3 of Fig. 2.

Fig. 4 is a fragmentary elevational view looking in the direction of the line 4—4 of Fig. 2.

Fig. 5 is a side elevational view of an adjustable chair constructed according to a modification of this invention.

Fig. 6 is a fragmentary enlarged perspective detailed view of a portion of Fig. 5 looking in the direction of the line 6—6 of Fig. 5.

Fig. 7 is a horizontal sectional view taken on the line 7—7 of Fig. 6.

Fig. 8 is a vertical sectional view taken on the line 8—8 of Fig. 7.

Fig. 9 is perspective view showing a covering material used for the chair.

Fig. 10 is an enlarged perspective detail view of Fig. 9.

The adjustable chair, in accordance with this invention, includes a flexible frame 10 having

a pair of spaced forwardly extending feet portions 10^a for resting on the floor and continuing into a pair of upwardly extending front portions 10^b continuing into a pair of rearwardly extending side portions 10^c. A horizontal bar 11 is mounted across the front portions 10^b at an intermediate height. A transverse back portion 12 depends from the rear ends of the side portions 10^c. A chair back 13 is pivotally mounted on said transverse back portion 12. A chair seat 14 is pivotally connected with said chair back 13 and extends forwards and rests on said horizontal bar 11 and is adapted to maintain various fixed positions on said horizontal bar.

15 The forwardly extending feet portion 10^a are provided with downturned rear ends 10^{aa} and downturned front ends 10^{bb}. The forwardly extending feet portions 10^a rest upon these downturned ends 10^{aa} and 10^{bb}. An auxiliary horizontal bar 11^a is mounted across the upwardly extending front portions 10^b at a point below the horizontal bar 11.

20 In the form of the invention illustrated in Figs. 1—4 inclusive the transverse back portion 12 depends from the rear ends of the side portions 10^c by reason of downwardly extending portions 10^{cc} which connect the rear ends of the side portions 10^c with the ends of the transverse back portion 12. Several loop elements 15 are welded to the sides of the chair back 13. The transverse back portion 12 extends through these loops 15. The chair back 13 comprises substantially a frame section having side arms 13^a, a bottom arm 13^b, and a top arm 13^c. The top arm 35 13^c is set rearwards of the top ends of the side arms 13^a.

30 The chair seat 14 comprises a substantially U-shaped member having side arms 14^a, a front arm 14^b which is offset downwards from the ends 40 of the side arms 14^a. The rear ends of the side arms 14^a are pivotally connected with the bottom ends of the side arms 13^a of the chair back by pintles 16. Several transverse bars 17 are mounted between the side arms 14^a. Toothed 45 shaped members 18 are formed upon, or mounted upon the bottom sides of the side arms 14^a and are adapted to engage the bar 11 to hold the chair seat 14 in the various fixed positions previously mentioned.

50 Fig. 1 illustrates the adjustable chair in one condition. It may be placed in the condition shown in Fig. 2 by first lifting the front end of the seat 14 and then forcing the seat rearwards and allowing the front end to move downwards so that the toothed shaped members 18 re-en-

gage the bar 11 in a different position. This adjustment changes the inclination of the chair back.

In Figs. 5 to 8 inclusive a modified form of the invention has been disclosed which distinguishes from the prior form in the provision of a means for varying the distance of the transverse back portion 12' from the side portions 10^{cc}. More specifically, each side portion 10^{cc} has a tubular member 20 mounted on its rear end. An anchor member 21 is disposed within each tubular member 20. Each anchor member 21 is attached to one end of a cable 22. A tubular member 23 is threadedly engaged in the rear end of each tubular member 20 and serves to firmly hold the anchor members 21 in position. The extended ends of the cables 22 engage into the ends of the transverse back portion 12'. The transverse back portion 12' is of tubular construction. Each end of the transverse back portion 12' is formed with a split 25 having lugs 26 upon the sides thereof. A screw 27 engages through one of the lugs and threadedly engages the other of the lugs of each end of the transverse back portion, whereby the screws 27 may be turned tight for clamping the cables 22 in position.

In Figs. 5 and 6 the adjustable chair is shown in one condition. The transverse back portion 12' is capable of swinging forwards and rearwards on the cables 22. If it is desired to vary the distance of the transverse back portion 12' from the said side portions 10^{cc} it is merely necessary to loosen the screws 27 and then let in or pull out the cables 22 from the ends of the transverse back portion 12'.

In other respects this form of the invention is similar to the previous form and like parts are identified by like reference numerals.

In Figs. 9 and 10, the chair covering material 30 is shown to be secured in tubular end members 31 slotted at 32. The covering material 30 made of a backing sheet of leather 33 and a front corrugated sheet of leather 34, are joined together by stitches or the like 35. The ends of sheets 33 and 34 are folded over to form a heavy edge 36, to prevent the covering material 30 from sliding out of the slotted tubing 31.

In other respects this form of the invention is similar to the previous forms.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An adjustable chair, comprising a flexible frame having a pair of spaced forwardly extending feet portions for resting on the floor and continuing into upwardly extending front portions continuing into rearwardly extending side portions, a horizontal bar across said front portions, a transverse back portion depending from the rear ends of said side portions, a chair back pivotally mounted on said transverse back portion, and a chair seat pivotally connected with said chair back and extending forwards and rested on said horizontal bar and adapted to maintain various fixed positions on said horizontal bar, and means for varying the distance of said transverse back portion from said side portions.

2. An adjustable chair, comprising a flexible frame having a pair of spaced forwardly extending feet portions for resting on the floor and continuing into upwardly extending front portions continuing into rearwardly extending side portions, a horizontal bar across said front portions, a transverse back portion depending from the rear ends of said side portions, a chair back pivotally mounted on said transverse back portion, and a chair seat pivotally connected with said chair back and extending forwards and rested on said horizontal bar and adapted to maintain various fixed positions on said horizontal bar, and means for varying the distance of said transverse back portion from said side portions, comprising cables mounted upon the rear ends of said rearwardly extending side portions, said transverse back portion being of tubular form and said cables being engaged into the ends thereof, and means for holding said cables in various positions in the ends of said transverse back portion.

3. In an adjustable chair, a frame of tubular material having spaced side portions and downwardly extending front portions, a horizontal bar across said front portions, a chair seat having its front end resting on said horizontal bar, a chair back having its bottom end pivotally attached to said chair seat, a tubular transverse bar positioned between the back ends of said side portions and pivotally supporting said chair back, a cable for the rear end of each of said side portions, an anchor member mounted on one end of each of said cables and freely engaged into the ends of said side portions, means for holding said anchor members in position within the ends of said side portions, said cables having their free ends extended into the ends of said transverse bar, and means for clamping the ends of said transverse bar in various positions along the length of said cables.

4. In an adjustable chair, a frame of tubular material having spaced side portions and downwardly extending front portions, a horizontal bar across said front portions, a chair seat having its front end resting on said horizontal bar, a chair back having its bottom end pivotally attached to said chair seat, a tubular transverse bar positioned between the back ends of said side portions and pivotally supporting said chair back, a cable for the rear end of each of said side portions, an anchor member mounted on one end of each of said cables and freely engaged into the ends of said side portions, means for holding said anchor members in position within the ends of said side portions, said cables having their free ends extended into the ends of said transverse bar, and means for clamping the ends of said transverse bar in various positions along the length of said cables, said first means comprising tubular members coaxially mounted on said cables behind said anchor members and threadedly engageable into the rear ends of said side portions.

5. In an adjustable chair, a frame of tubular material having spaced side portions and downwardly extending front portions, a horizontal bar across said front portions, a chair seat having its front end resting on said horizontal bar, a chair back having its bottom end pivotally attached to said chair seat, a tubular transverse bar positioned between the back ends of said side portions and pivotally supporting said chair back, a cable for the rear end of each of said side portions, an anchor member mounted on one

end of each of said cables and freely engaged into the ends of said side portions, means for holding said anchor members in position within the ends of said side portions, said cables having their free ends extended into the ends of said transverse bar, and means for clamping the ends of said transverse bar in various positions along the length of said cables, said transverse bar having split ends into which the free

5 ends of said cables extend, said latter means comprising a pair of lugs mounted on each end of said transverse bar on either side of the splits, and screws freely extended through one lug of each pair of lugs and threadedly engaging the other lug of the pair for drawing the split ends together.

EINAR ANDERSON.
